UNITED STATES PATENT OFFICE

THOMAS E. MURRAY, JR., OF BROOKLYN, AND FRANK C. REYNOLDS, OF NEW YORK, N. Y.,
ASSIGNORS, BY MESNE ASSIGNMENTS, TO AMERICAN RADIATOR & STANDARD
SANITARY CORPORATION, A CORPORATION OF DELAWARE

RADIATOR INCLOSURE

Application filed August 3, 1929. Serial No. 383,194.

In certain prior applications of Bennett, Ser. No. 355,059, filed April 15, 1929 and Reynolds, Ser. No. 377,392 filed July 11, 1929, there are described certain methods of supporting and inclosing radiators for heating the air of a room. The present application is based on improvements in the same class of structures.

The accompanying drawings illustrate 10 embodiments of the invention.

Fig. 1 is a vertical section partly in elevation of an inclosed radiator;

Fig. 2 is a perspective view of a set of shims for adjusting the top of the inclosure;

Fig. 3 is a side elevation illustrating an alternative method of such adjustment;

Fig. 4 is a plan view of the lower end of one of the brackets;

Fig. 5 is a horizontal section approximately on the line 5—5 of Fig. 1;

Fig. 6 is a front elevation of a bracket;

Fig. 7 is a perspective view of a panel forming the front and sides of the inclosure;

Fig. 8 is a perspective view of the complete structure mounted in line with one of the windows of a room;

Fig. 9 is a vertical section of a hanger and adjacent parts showing an adjustment for irregular walls;

Fig. 10 is a perspective view of a panel showing a similar adjustment.

The radiator may be of various designs. In the case illustrated it is of the Murray type. The heating element consists of a steam pipe arranged in three longitudinally extending sections 1, 2 and 3 spaced apart vertically. To this pipe is applied a structure of extended area consisting of two sheets of copper or similar sheet metal 4 applied to opposite sides of the pipe and providing vertical flues open at top and bottom for heating and inducing an upward draft of the air so as to circulate it through the room to be warmed.

Applied to the face of the wall 5 are two brackets, one near each end of the radiator. Each bracket consists of a channel 6 with stiffening flanges 7 projecting forward. The upper end of each bracket is bent to form a rearward hook 8 which fits over a flange 9

of a longitudinally extending plate 10 which is shaped (in various ways according to the shape of the upper edge of the wall) to extend over the sill portion 11 of the latter and to bring the flange 9 approximately flush 55 with the face of the wall 5.

The brackets 6 thus hang against the wall. At their lower ends they are bent forward to provide arms 12 for supporting the lower edge of the panel constituting the front of 60 the inclosure. In order to space the lower edge of the panel exactly from the wall, the arm 12 carries an extension 13 with an upward flange 14 at its front end. The extension is fastened by means of a screw 15 65 threaded into the extension and passing through a slot 16 in the arm 12.

Applied to the front of the brackets are hangers which are used for supporting the radiator and for supporting the top of the 70 inclosure. Each hanger consists of a vertical plate 17 provided on its rear edge with lugs 18 (Figs. 3 and 5) which are passed through suitably located holes in the brackets 6 and bent over to fasten the hanger to 75 the bracket.

The upper portion of the bracket is provided with an approximately semi-circular recess 19. The lower edge 20 is tapered and then curved downward to provide a concave 80 portion 21 adapted to bear down on one of the sections of pipe and to provide a stop against backward movement of the pipe.

To hang the radiator, the upper pipe section 1 is arrested in the recesses 19, holding 85 the radiator in approximately horizontal position. It is then swung down to the vertical position so as to thrust the hangers between the pipe sections 1 and 2, bringing the latter up against the shoulders 21. For this 90 purpose the corrugated sheets 4 are apertured at the front and back as shown in Fig. 5. The front end of the hanger then projects beyond the front of the radiator.

The front portion has a lateral flange 22 95 which overlies the front of the radiator and carries a screw 23 which can be turned against the radiator in order to force the pipe section 2 against the overhanging stop 21. Thus the hanger bears upward and downward at op- 100

posite sides on the pipe sections and the radiator is prevented from vertical movement in either direction and is held against lateral movement by the screws at the front. These screws also serve as abutments for the front panel, hereinafter described.

A similar hanger or plate 17 is used in the upper end of the inclosure to support the top plate. For economy in manufacture it is made identical with the hanger which carries the radiator. But the notched and curved upper and lower edges are not necessary in this use of the hanger and its shape may be varied in other ways.

On top of these hangers or supports 17 there rests a plate 24 perforated to permit the free exit of the heated air and connected by spot welding to angles 25 which are mounted on the front of a flange 26 forming part of a sill plate 27. Thus the top plate 24 of the inclosure is set to project a certain distance from the window and its level is fixed parallel with that of the window sill (which is generally carefully determined by the builder).

Similarly the plate or strips 10 are set to project a certain distance from the window and to be level therewith, whence it follows that the lower ends of the brackets 6 will also be leveled or alined parallel with the window sill in the longitudinal direction of the inclosure.

The top-supporting plates 17 may be made adjustable on the rear brackets 6. The construction is simplified, therefore, by fixing them a certain height on these brackets. To bring the supports up to the desired level for the plate 24, we may use shims of suitable thickness. Fig. 2 shows two shims 27 and 28, being short channels of different thicknesses adapted to be arranged on top of the plates 17 as shown in Fig. 1.

An alternative arrangement is shown in Fig. 3, by which the height of the plate may be varied. In this case the plate 17 is provided near its upper end with a series of threaded holes 29 at an angle to the horizontal. A separate extension plate 30 is arranged with holes 31 in horizontal alignment. A screw 32 passed through any one of the holes 31 and threaded into the corresponding one of the holes 29 will serve to bring the top of the support at a desired level.

The top plate 24 has along its front edge a downwardly depending flange 33 which is engaged over the upper edge of a front plate 34. This plate has an inward stiffening flange 35 along its upper edge. Near its lower edge there is welded on its rear face a stiffening plate 36 with an inward flange 37 and with a depending spaced flange 38 forming with the lower edge of the front plate a groove fitting over the flange 14 of the lower ends of the brackets 6.

The front plate, after the setting of the

radiator and the top plate in position, is introduced by thrusting its upper edge behind the flange 33, lifting it and lowering it over the flanges 14 at the bottom. Its intermediate portions may bear against the screws 23 and be thus laterally supported.

The front plate may be separate from the sides of the inclosure as in the Bennett application above referred to. Preferably, however, the front plate 34 and the sides 35, Fig. 7, are united in a single removable panel which is inserted in the manner above described and locked in place at a correct distance, top and bottom, from the wall.

The lower end of the inclosure is open to permit free access of the cool air near the floor. Or the lower end may be closed, and openings provided in the lower part of the front plate for the same purpose.

The brackets 6 may be fastened to the wall instead of being hung from their upper ends as above described. Or even when they are so hung they may be fastened to the wall to give the entire structure greater rigidity.

A simple means of fastening is shown in Fig. 1. It consists of strips 39 welded on to the lower part of the brackets, extending downward somewhat below the finished floor level and having forward flanges 40 which are embedded in the floor.

The face of the wall 5 is not always even and truly vertical. The difference may not be sufficient to affect the hanging of the radiator and the installation of the inclosure. But for taking care of any lack of perfect verticality, the parts may be modified as shown in Figs. 9 and 10.

In Fig. 9 the top supplementary brackets 17 carry adjustable hooks 41 having slots 42 through which pass screws 43 threaded into the upper parts of the brackets. According to the adjustment by the slots 42, the brackets 17 and the upper ends of the main brackets 6 will be supported closer to or farther away from the face of the wall 5.

The sides 35 of the panel, Fig. 10, may also be provided with molded rear edges 44 which can be adjusted toward and from the wall and with a certain angular variation from the vertical. Each such molding has welded to its rear portion a plate 45 adapted to overlap the inner face of the side member 35 and to hold the latter between it and the molding 44. The plate 45 is threaded to receive screws 46 which pass through horizontal slots 47 in the sides 35 to permit the adjustment described.

Where the space of the lower portion of the inclosure does not have to be adjusted, the lower ends 12 of the brackets 6 may be extended forward integrally and bent up to form flanges 14^a as shown in Fig. 9.

Various other modifications may be made by those skilled in the art without depart-

ing from the invention as defined in the appended claims.

1. An inclosure for radiators comprising a top, a side and a front in combination with brackets supported from and alined with a window sill of a room the lower edge of the front being supported and alined and spaced from the wall by said brackets.
2. An inclosure for radiators comprising a top, sides and a front in combination with brackets mounted on a wall and means extending forward from said brackets for supporting the top of the inclosure independently of the sides and front.
3. An inclosure for radiators comprising a top, sides and a front in combination with brackets mounted on a wall and means extending forward from said brackets for supporting the top of the inclosure at an adjustable height.
4. An inclosure for radiators including a top, sides and a front in combination with brackets against a wall supported at their upper ends and anchored to the wall and extending forward to the front of the inclosure and supporting said front.
5. An inclosure for radiators comprising a separate panel adapted to be applied after the radiator is supported in position, said panel comprising a front and side walls in combination with brackets mounted against a wall and extending forward to the front of the inclosure and supporting said front.
6. The combination with an inclosure for radiators of means fixed with respect to a window sill of the room for supporting the inclosure with its top at an adjustable height with respect to the side and front portions of the inclosure.
7. An inclosure for radiators in combination with brackets for supporting it and means for supporting said brackets from a window sill at an adjustable distance from a wall.
8. An inclosure for radiators including a front means mounted on a wall for directly supporting said front and means for adjusting its distance from the wall.
9. An inclosure for radiators including a front means mounted on a wall and directly supporting said front and means for adjusting the angle which it makes with the face of the wall.
10. An inclosure for radiators including sides, uprights mounted against a wall in line with the sides, and means for adjusting the forward position of the sides with relation to said uprights.

In witness whereof, we have hereunto signed our names.

THOMAS E. MURRAY, JR.
FRANK C. REYNOLDS.
